F. C. MCINTIRE

SCRAPER

Filed Nov. 8 1926

UNITED STATES PATENT OFFICE.

FRANK C. MCINTIRE, OF STOCKTON, CALIFORNIA.

SCRAPER.

Application filed November 8, 1928. Serial No. 146,945.

This invention relates to improvements in earth scraping and transporting devices, my principal object being to provide an apparatus for the purpose so constructed that dirt as scraped up is immediately transferred to a wheel supported bowl. The advantages of this arrangement are great. It is generally recognized that the greatest obstacle to scraping and transporting large loads is the resistance of the dirt to piling up and being dragged along the ground, so that ever increasing draft power is necessary to scrape and drag along a gradually increasing mass of dirt. Once a large body of dirt however is placed in a wheel supported receptacle, the hauling of the receptacle and its load becomes a very easy matter requiring relatively little power.

With my improved apparatus the above ideal conditions are obtained and only a very small body of scraped dirt remains in dragging relation with the ground at any time. The scraper may therefore be made in any size practicable to carry a correspondingly large mass of dirt without having to consider the limitations imposed by available power or other draft means, as must now be done when designing scrapers of ordinary construction.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of my improved scraper.

Fig. 2 is a sectional plan of the same.

Fig. 3 is a detailed section taken on the line 3—3 of Fig. 2 to show the bowl upsetting trip structure.

Fig. 4 is a top plan detail of a holding means for the scraper blade raising lever.

Fig. 5 is a cross section on the line 5—5 of Fig. 4, showing the lever in its raised position.

Referring now more particularly to the characters of reference on the drawings, the machine comprises a horizontal frame structure consisting of side beams 1 with cross

beams 2 at its ends. Journaled in and extending between the beams 1 intermediate their ends is a shaft 3. Turnable on the shaft adjacent and inside the beams 1 are wheels, each including a tread band 4 and a plurality of wide flat spokes 5. The two wheels are rigidly connected together to turn as a unit by means of transverse bands 6 extending between corresponding spokes of the wheels at their outer ends, these bands being concentric with the tread, the same width as the spokes, and preferably but not necessarily formed integral therewith. Likewise extending between corresponding spokes of the wheels are plates 7 abutting against one edge face of the spokes and extending from the bands 6 toward the shaft 3 a certain distance. Each set of members 6 and 7 forms a scoop which is open rearwardly of the direction of movement of the wheel when at the bottom thereof. Fixed on the shaft 3 is a cylindrical bowl 8 cut away for its full width a certain distance above the shaft so as to be open on top. The bowl is concentric with the shaft and with the wheels and extends closely between the spokes of the two wheels but with a working clearance therebetween. The inner ends of the scoop plates 7 clear the periphery of the bowl just sufficiently to prevent any possibility of engaging the same.

Disposed under the frame rearwardly of the wheels is a transverse scraper blade 9 set at a suitable vertical angle and supported from the frame by bars 10 which extend from said blade to the ends of the shaft 3 outside the beams 1, the bars being turnable on the shaft. The scraper blade is disposed relative to the wheels and scoops so that with the forward movement of the machine and the rotation of the wheels, only a small mass of dirt will be scraped and piled in front of the blade before the forward portion of such dirt will be successively engaged by the rotating scoops which immediately raise the dirt and deposit it in the bowl. The bowl is therefore being constantly filled as the machine moves forward, while the amount of scraped dirt remaining engaged with the ground and being dragged forward is constantly kept very small, as will be evident.

The blade is raised from engagement with the ground when desired and necessary by means of a vertical lever 11 pivoted thereon

centrally of its width. This lever passes between longitudinally extending guide plates 12 fixed on the rear beam 2. Hinged onto the plates at their forward ends and 5 on top are transversely opposed catch plates 13, yieldable upwardly, whose free ends normally lie in adjacent relationship to each other, as shown in Fig. 4. This lever carries a forwardly projecting pin or bar 14 above the guide structure which is adapted, when the lever is moved forwardly so as to project between the plates 13, to then project into the path of movement of the scoop members 6. When the lever-pin is thus engaged with any member 6 the rotation of the 10 wheels causes the pin and lever to be raised until the diverging path of movement of the members 6 relative to the lever causes the pin to be released. The lever is then held from dropping by an adjustable block 15 thereon. This block is normally below the plates 13, but with the upward movement of the lever it will spread and lift the plates and pass above the same. Then when 20 the pin 14 is released the block 15 acts as a stop, in connection with said catch plates, to prevent downward movement of the lever, as shown in Fig. 5. The scraping blade will therefore be held raised. When it is desired 25 to lower the blade it is only necessary to pull the lever rearwardly to clear the plates 13, the latter terminating a sufficient distance ahead of the beam 2 to permit of the unobstructed passage of the lever and block 30 between the guides rearwardly of said plates.

To enable the bowl to dump it must be tipped upside down or turned through a half revolution of the shaft. This may be 35 done in various ways, either by hand or power. In the present instance I have shown a power actuated mechanism comprising a lever 16 secured to the shaft 3 and rotated between a beam 1 and the adjacent 40 wheel. The lever normally extends rearwardly to a point adjacent the beam 2, so that its corresponding end may be manipulated by hand; and has a lateral pin 17 extending toward the wheel to project into the 45 path of movement of the spokes 5. The pin only thus projects however when the lever (which is of spring material and transversely yieldable) is sprung inwardly and clear of a catch plate 18 mounted on the beam 1. 50 The lever is held in that position until a spoke engages the pin, when said lever will of course be rotated by the continued rotation of the spoke. The lever and bowl being both secured to the shaft, said bowl is 55 then arranged in driving relation with the wheel and will of course rotate therewith. As the bowl approaches an upset position the lever 16 engages a sloping release member 19 or cam fixed on the forward beam 2. 60 65 This member is arranged to cause the adja-

cent end of the lever to be moved outwardly or toward the adjacent beam 1 so that the pin will be pulled clear of the spoke. The lever then engages a cradle 20, formed with the member 19, preventing further downward movement of the lever and consequently preventing further rotation of the bowl. When it is desired to right the bowl the lever is pulled by hand in the opposite direction to return it to engagement with the catch member 18. 70 75

When the bowl is discharged some of the dirt will fall on the buckets underneath and will be raised again as the wheels rotate. Such dirt, however, will then drop onto the inverted and downwardly sloping surface of the bowl and will slide to the ground instead of falling into the bowl. Thus after about two revolutions of the wheels all the dirt will be taken care of and properly discharged clear of the machine. 80 85

The majority of the wheel spokes are preferably riveted to the wheel treads and hubs. Some of the spokes, however, may be bolted to the treads and hubs so that they may be 90 removed therefrom with the corresponding scoop members as a unit. This will permit the bowl to be inserted and withdrawn from between the wheels when assembling the machine or when desiring to dismount the 95 bowl for repairs or replacement. 100

The cross members 6 between the wheels not only form the bottoms of the scoops, but also serve to support the weight of the machine in addition to the wheel-treads. This is especially valuable in maintaining the machine on the surface when working in sand and loose dirt, giving a caterpillar tread effect. 105

A further object of the invention is to produce a simple and inexpensive device and yet one which will be exceedingly effective for the purpose for which it is designed. 110

While this specification sets forth in detail the present and preferred construction of the device, still in practice such deviations from such detail may be resorted to as do not form a departure from the spirit of the invention, as defined by the appended claims. 115

Having thus described my invention what I claim as new and useful and desire to secure by Letters Patent is:

1. A scraper including a frame, a wheel structure supporting the same, a transverse scraper blade behind the wheel structure, a connection between the blade and frame pivotally connected to the latter, an upstanding lever connected to the blade, a transverse projection on the wheel structure, a forward projection on the lever, the lever being arranged to be swung forwardly at will to cause the projection thereon to initially overhang the wheel projection, whereby with the forward rotation of the wheel the lever will be raised a certain distance before 120 125 130

the projections clear each other, and means then acting automatically to prevent lowering movement of the lever.

2. A scraper including a frame, a wheel structure supporting the same, a transverse scraper blade behind the wheel structure, a connection between the blade and frame pivotally connected to the latter, an upstanding lever connected to the blade, means operating at will between the lever and wheel structure for causing the lever to be raised a certain distance with the forward rotation of the wheel, a guide through which the lever passes, an enlargement on the lever, and an upwardly yielding plate on the guide, normally engaging the lever, the block being disposed on the lever so that it will move above the plate when the lever has been raised said certain distance.
3. A scraper including a frame, wheels supporting the same, a bowl turnably hung in the frame, a lever mounted in fixed and radial connection with the bowl to turn therewith, means normally holding the lever against movement, means for placing the lever into driving engagement with one of the wheels when the lever is released from the holding means whereby the bowl will rotate with the wheel, and means on the frame to engage the lever when the latter has rotated with the wheel to a bowl-upsetting position and move said lever out of driving engagement with the wheel.
4. A scraper including a frame, wheels supporting the same, a bowl turnably hung
- in the frame, a lever mounted in fixed and radial connection with the bowl to turn therewith, means normally holding the lever against movement, means for placing the lever into driving engagement with one of the wheels when the lever is released from the holding means whereby the bowl will rotate with the wheel, and a common means on the frame for moving the lever out of driving engagement with the wheel after the lever and bowl have moved to a bowl-upsetting position and for also holding said lever against further movement in the same direction.
5. A scraper including a frame, a transverse shaft turnably mounted thereon, a bowl fixed on the shaft, wheels turnable on the shaft, spokes for the wheels, a transversely flexible lever fixed on the shaft and projecting radially therefrom, a stop on the frame normally engaging the lever to prevent turning movement thereof, a pin projecting laterally from the lever for engagement with a spoke of one of the wheels when said lever is flexed transversely and clear of the stop, and a cam mounted on the frame in the path of rotative movement of the lever to engage and draw the same laterally so that the pin is disengaged from the spoke, after said lever has rotated to an arcuate extent sufficient to place the bowl in an inverted position.

In testimony whereof I affix my signature.

FRANK C. McINTIRE.
